UNITED STATES PATENT OFFICE.

ANDRÉ JULES MICHELIN, OF PARIS, FRANCE, ASSIGNOR TO MICHELIN ET CIE., OF CLERMONT-FERRAND, FRANCE, A CORPORATION OF FRANCE.

DESIGN FOR AN AIR-PUMP CASING.

Application filed October 4, 1928. Serial No. 28,366. Term of patent 14 years.

To all whom it may concern:

Be it known that I, ANDRÉ JULES MICHELIN, a citizen of France, residing at Paris, France, have invented a new, original, and ornamental Design for Air-Pump Casing, of which the following is a specification, reference being had to the accompanying drawings, forming a part thereof.

The figure is a perspective view of the air

pump casing showing my new design, the opposite side of the casing being similar to the sides shown.

I claim:

The ornamental design for an air pump casing, as shown and described.

In testimony whereof I affix my signature.

ANDRÉ JULES MICHELIN.
